UNITED STATES PATENT OFFICE

GEORGE G. BRACKETT, OF ROCHESTER, WASHINGTON

GRAVEL SPREADER

Application filed March 26, 1930. Serial No. 439,005.

My invention relates to road working machinery, and in particular to a device for spreading gravel over roads.

In the maintenance of gravel roads, it is customary to employ a road scraper which scrapes the ridges from the road and removes the material down to an even, hard roadbed. The removed material is deposited usually along the crown of the road as a ridge, and this ridge must later be spread over the surface of the road. While it remains in the road, it is a source of annoyance and some danger to traffic, and the movement of the scraper back along the ridge to spread it, requires that traffic be further blocked, with the possibility of accident to motorists who may not observe the scraper in the center of the road, as for instance, upon rounding a curve.

It is an important object of my invention to provide an assemblage of road-working devices operating as a unit, whereby the gravel which is removed from the road surface and piled in a ridge is immediately spread over the scraped surface, thus avoiding the danger of the ridge, the loss of time required to again traverse the road to spread it, and the danger and interruption to traffic ensuing from this spreading action.

It is also an object to spread the removed gravel as a cushion over the scraped surface most evenly and perfectly, and with the minimum of interruption or danger to traffic.

It is a further object to provide a gravel spreader for use in work upon roads, containing adjustments which enable it to function perfectly and to apply an even cushion of material over the scraped surface, and a device which projects the minimum into the opposite traffic lane, and which is so closely coupled to the tractor, usually the scraper, that no additional danger ensues from its use in conjunction therewith. In other words, it is my object to so closely couple the spreader with the scraper that an on-coming motorist, who must in any event avoid the scraper, will not have to watch additionally to prevent collision with the spreader.

A further object is to provide a gravel spreader which is adjustable in angle and in

elevation, and one which can be easily turned over to permit it to be run in the opposite direction, and so constructed that this turning over may be accomplished by, at the most, two workmen.

Other objects, and more especially such as relate to the structural details of my invention, will be understood from a study of the specification, of the claims terminating the same, and of the accompanying drawings, wherein my invention is shown in a form which is at present preferred by me.

My invention comprises the novel parts and the novel combination and arrangement thereof, as shown in the drawings, described in the specification, and as will be more particularly defined by the claims which terminate the same.

Figure 1 is a view in plan showing the essential features in the combination of my spreader with a road scraper.

Figure 2 is a plan view of the spreader coupled to a tractor member.

Figure 3 is a rear elevation of the spreader.

Figure 4 is a side elevation of the spreader, the near wheel being removed.

Figure 5 is an elevation of the mold-board and spreader blade.

Figure 6 is a detail in plan view of a modified form of holding means for the vertical adjustment.

By reference to Figure 1, it can be seen that the scraper blade 9, carried upon a vehicle which is in its essence a tractor, indicated at 90, is inclined and is so held down that it cuts into the road surface and removes the high spots so that there is left behind it a surface which is scraped clean of loose material and which is substantially in one plane, that is to say, without ruts, hollows and chuck holes. The removed material is deposited in a ridge, indicated by the letter R, and if the usual practice is followed this ridge R becomes a menace to traffic, especially when it becomes necessary to remove it. It is sometimes the practice to cause a spreader vehicle to follow behind the scraper and to spread this ridge, but this necessitates that a driver coming from the opposite direction must avoid not only the scraper but

also the following spreader, and it means that drivers coming from the same direction, because of the ridge and because of the separation between the two road-working vehicles, 5 may not readily pass the group, and thus traffic is considerably impeded and accidents may result from impatience on the part of drivers to pass the road-working group.

Accordingly, I provide a spreader blade 1, 10 which is carried upon a main frame 2, this being supported upon the wheels 3 and 30, the blade being angularly disposed relative to the frame, and lying in advance of one of the wheels, as 30, and behind the other wheel 15 3, so as to be compact. Now, the whole spreader is closely coupled to follow behind the tractor 90, which usually will also carry the scraper blade 9, and thus coupled, as for instance, by the links 91, the spreader forms 20 in effect a part of a single road-working machine, and the inner edge of the spreader blade, which forms the forward edge thereof, need project only far enough to engage and include the material in the ridge R. To further assist in encompassing this ridge and distributing it, its leading end may be curved forwardly, as is indicated at 10.

The blade 1 is preferably formed in two parts, each identical, and supported upon a 30 mold-board 11, which is provided with apertures at 12 and 13. The mold-board may be formed of several pieces secured together, and in this way or in any other suitable way the frame 2 is permitted to pass through the 35 apertures 12 and 13. Journal bearings 14 and 15 are secured upon the mold-board adjacent the apertures 12 and 13 respectively, and a pin 16 is received in these bearings and in bearings 24 and 25 respectively secured to 40 the frame, and held thereto by the removable bolts 26, received in spaced holes 21 of the frame, whereby the mold-board and spreader blade may be adjusted in angular position relative to the frame.

45 The frame is supported upon two opposite wheels, as has been pointed out, but these wheels are not secured directly to the frame, but upon the outer or crank ends of shafts 31 and 32 respectively. The crank arms 33 50 of these shafts are substantially equal in length, and may be thrown into a selected angular position by suitable means, such as the worm gears 34 and 35 respectively, with which are engaged the worm pinions 36 and 55 37, journaled in the frame 2. The two shafts 31 and 32 are independent, but preferably are aligned. In order to enable the spreader blade 1 to extend between the wheels and transversely of the frame, I prefer that 60 one of these shafts be short, as for instance, the shaft 31, and that the other be longer, so that the worm gear 35 and the adjusting means may be located at one side of the frame, preferably in advance of 65 the spreader blade. The adjustment of these

wheels 3 and 30 may be accomplished before the vehicle starts and the adjustment held by engaging a plate 38 (see Figure 6) with the squared end of the worm pinion shaft, or they may be adjusted during operation by the 70 operator seated in the tractor 90, by means of extension shafts 39, which engage with the ends of the worm pinion shafts by a suitable universal connection, and which are supported in position for operation by the operator 75 in a removable frame 22, secured to the forward part of the frame 2. This frame 22 may be secured in position by such means as the wing nuts 23, for a reason which will appear hereafter, making the frame readily 80 removable.

The spreader blade 1, and the associated mold-board 11, comprise a total height approximately the same as the height of wheels 3 or 30. By means of the adjustment permitted by the crank arms 33, the wheels may be projected below the spreader blade to support its lower edge at any selected height above the hard surface of the scraped road. Furthermore, the entire spreader may be 90 turned over, resting upon the wheel 30 and the inner end of the spreader blade, by two men at the most, once the frame 22 and the control shaft 39 have been removed temporarily. When thus reversed, as indicated in 95 dotted lines in Figure 2, it is ready to traverse the road in the opposite direction, and this will be found of benefit where the facilities for turning around are not good. However, the device is so arranged and is so closely coupled to the tractor 90, by preference, 100 that the tractor may turn around without uncoupling the spreader therefrom.

Because of the independent control of the elevation of the two wheels 3 and 30, the inner wheel 30, which will ride upon the cushion of gravel spread immediately in advance of it by the spreader blade, may be slightly higher than the outside wheel 3, which rests upon the hard-scraped roadway. Adjustments in elevation of the spreader blade and of its angular position may be made at will to accommodate conditions as they are found, and the entire work of scraping and spreading gravel over the roadway may be accomplished by a 110 single vehicle under the control of one or two men, with the minimum of interruption or danger to traffic.

What I claim as my invention is:

1. A gravel spreader comprising a frame, 120 a pair of oppositely disposed supporting wheels therefor, a spreader blade of a height approximately equal to the height of said wheels, and extending angularly transversely of the frame, one end lying in advance of the wheel at that side, and the other end lying behind the opposite wheel, and each edge of said blade being formed and adapted for spreading, whereby the spreader may be turned over as a unit. 130

2. A gravel spreader comprising a frame, a short and a long crank shaft journaled in said frame and extending transversely thereof, a wheel upon the outer crank end of each shaft, 5 a worm gear upon the inner end of each shaft, a worm pinion meshing therewith, and a spreader blade extending transversely of said frame from behind the short shaft and in advance of the long shaft.
- 10 3. A gravel spreader comprising a frame, a short and a long crank shaft journaled in said frame and extending transversely thereof, a wheel upon the outer crank end of each shaft, a worm gear upon the inner end of each 15 shaft, a worm pinion meshing therewith, a spreader blade extending transversely of said frame from behind the short shaft and in advance of the long shaft, and means for adjusting the angular position of the spreader blade.
- 20 4. A gravel spreader comprising a main frame, a pair of crank shafts journaled in said frame and extending transversely thereof, a supporting wheel upon the outer crank end of each shaft, means at the inner end of each shaft for oscillating the same, a spreader blade extending transversely of the frame, and lying behind one wheel and in advance 25 of the other, said blade being of a height, and formed on each edge, to permit the spreader to be turned over to scrape with either edge, a removable frame securable upon said main frame, and means supported in said removable frame, and detachably connected to the 30 shaft-oscillating means, for controlling the elevation of the main frame and scraper blade relative to the roadway, by an operator upon a tractor in advance of the spreader.
- 35 5. A gravel spreader comprising a frame having a segmental portion at one side, supporting wheels at opposite sides of the frame, a scraper blade extending diagonally across the frame and apertured at one end to pass over the segmental portion thereof, a pivotal support for the opposite end of the blade, at the center of curvature of the segmental portion, and means to support the apertured end of the blade at selected points along the segment.
- 40 6. A gravel spreader comprising a frame having a segmental portion at one side, supporting wheels at opposite sides of the frame, a scraper blade extending diagonally across the frame and apertured at one end to pass 45 over the segmental portion thereof, a pivotal support for the opposite end of the blade, at the center of curvature of the segmental portion, a two-part bearing member, one part being secured to the blade adjacent its aperture, and means to secure the other part at selected positions along the segment.
